LOW PROFILE AIR CONDITIONER FOR MOUNTING IN DOUBLE-HUNG WINDOWS

James W. Bruner, Sr., and George W. Sisk, Jr., Evansville, Ind., assignors to Whirlpool Corporation, Benton Harbor, Mich.

Filed June 5, 1972, Ser. No. 260,044

Term of patent 14 years

Int. Cl. D23—04

U.S. Cl. D23—141

FIG. 1 is a front elevational view of a low profile air conditioner for mounting in double-hung windows showing our new design;

FIG. 2 is a top plan view thereof; and

FIG. 3 is a left side elevational view thereof, the right side being similar.

The knobs are shown in broken lines in FIG. 3 for illustrative purposes only.

The air conditioner is broken away in FIGS. 2 and 3 to indicate indeterminate width.

We claim:

The ornamental design for a low profile air conditioner for mounting in double-hung windows, as shown and described.
